UNITED STATES PATENT OFFICE.

HAROLD BLYE, OF GRAND RAPIDS, MICHIGAN, ASSIGNOR TO NATIONAL BRASS CO., OF GRAND RAPIDS, MICHIGAN, A CORPORATION OF MICHIGAN.

GRAVITY-LATCH.

1,294,227.

Specification of Letters Patent. Patented Feb. 11, 1919.

Application filed October 26, 1918. Serial No. 259,765.

To all whom it may concern:

Be it known that I, HAROLD BLYE, a citizen of the United States of America, residing at Grand Rapids, in the county of Kent 5 and State of Michigan, have invented certain new and useful Improvements in Gravity-Latches; and I do hereby declare the following to be a full, clear, and exact description of the invention, such as will 10 enable others skilled in the art to which it appertains to make and use the same.

This invention relates to a latch particularly adapted for use in holding swinging doors closed though it is not in any measure 15 limited to the one use specified. It is an object and purpose of the invention to produce a latch entirely of sheet metal of few parts requiring a relatively small number of operations, and one in which a single latch 20 may be used on either a door swinging to the right or to the left, there being obviated the necessity of having two complete sets of dies for making the rights and lefts heretofore necessary to supply latches for both 25 types of doors. A further object of the invention is to produce a latch of extreme simplicity in construction and one which operates automatically as the door reaches closing position to hold the door in such position, release thereof being effected by a simple manual operation of a handle forming 30 one element of the latch structure. These features, together with others not specifically enumerated at this point will fully appear 35 from the following description taken in connection with the accompanying drawing showing a practical and working embodiment of the invention, in which drawings:

Figure 1 is a front elevation of the latch 40 applied to a door, a fragment of the door and of the casing or jamb therefor being shown.

Fig. 2 is a side elevation thereof.

Fig. 3 is a rear elevation of the latch 45 construction.

Fig. 4 is a front elevation of the latch housing, and

Fig. 5 is a fragmentary side elevation and 50 section of the connecting mechanism between the latch handle and the latch lever or bar.

Like reference characters refer to like parts in the different views of the drawings, and in all of the drawings the scale is substantially twice that of the latch as made.

55 The latch is designed to be attached ad-

jacent the free edge of the door 1, while the keeper is adapted for attachment to an adjacent portion of the door jamb or casing 2. The keeper comprises a plate 3 from which a hook 4 projects, it having an inclined front face 5 and a rear vertical shoulder 6 behind which the latch bar or lever is adapted to position when the door is closed. In practice the keeper is secured to the door jamb by any suitable means, such as the 60 screws 7 as shown.

The latch is formed from sheet metal, preferably, and comprises a housing having a front side 8 with rearwardly bent sides 9 and ends 10, said ends being bent upwardly 65 and downwardly, respectively, to form attaching sections 11 which parallel the front 70 8 of the housing and are adapted to lie against the front of the door, being secured thereto by any suitable fastening means 75 such as screws which pass through holes made in the sections 11, as shown in Fig. 1.

One of the sides 9 is turned under the front of the housing for a distance making a section 12 which lies against the front of 80 the door, which section at its free edge and substantially at its middle point has an integral lip 13 projecting therefrom turned upwardly at the end to enter an opening 14 made through the latch bar or lever 15. The 85 opening 14 is substantially at the middle of the lever 15, the same extending through a slot 16 cut in a side 9 of the housing and a distance beyond so as to pass over the hook 90 of the striker when the door is closed.

In the front 8 of the housing a central opening 17 is cut to leave two inwardly projecting tangs 18 which extend toward each other as best shown in Fig. 4. A post 19 passes through the opening 17 and is formed with a hole 20 therethrough at a point between its ends into which the tangs 18 may be inserted thereby pivotally mounting the post to turn on a horizontal axis. The inner reduced end 19^a of the post passes loosely 100 into an opening made through the inner end of the latch lever 15, while the other end passes through the upper end of an operating handle 21 and is headed over as shown at 19^b to secure the handle and post 105 permanently together. The lower end of the handle is formed into a ring 22 for ready engagement by the fingers in the manual operation of the same. It will be noted that the connection of the handle to the post per- 110

mits the turning of the handle about the axis of the post to a position directly opposite that shown in the drawings, and that while the drawings show the latch attached 5 to a door adapted to swing to the right, when the handle is turned around one hundred and eighty degrees and the latch inverted, it is adapted to be attached to doors swinging in the opposite direction the slot 10 being of sufficient length to permit the movement of the latch lever when the latch is used on either type of door.

When the latch is attached to the door and the keeper to the door jamb or casing, the 15 free end of the latch lever 15 passes across the meeting edges of the door and casing and is adapted to pass behind the vertical shoulder 6 of the hook 4 of the keeper, the door in such case being held against opening. To open the door it is merely necessary to grasp the ring 22 and pull outwardly thereon whereupon the inner end of the latch lever is depressed with a consequent elevation of the outer free end held by the 20 hook 4 to a point above the hook, whereupon the door may be swung to open position, it being apparent that the unlatching of the door is accomplished by one act of the operator, namely, an outward pull on the ring 22 of the handle. When the door is closed the outer end of the latch lever 15 strikes against the inclined face 5 of the keeper and rides upwardly thereon until it passes the nose of the hook, dropping behind the shoulder 6, making a very easily 25 operated latch for both closing and opening operations.

A latch of the character described may be made entirely from sheet metal by simple stamping and forming operations. It is particularly economical to manufacture having but four parts easily made and assembled, and the feature of universal application to both right and left swinging doors 45 is one of great merit, this coming from the attachment of the handle to the post described.

I claim:

1. A latch of the character described comprising a housing including a front and inwardly turned sides and ends, one of said sides being slotted substantially its entire length and having an integral section turned inwardly under the front of the 55 housing and spaced therefrom, said section terminating in a centrally located upturned lip, and said front having an opening therethrough with integral tangs extending toward each other from opposite sides of the 60 opening, a latch lever having two openings therethrough, one adjacent the inner end of the lever and one adjacent the middle of the lever, said lever being located in the housing with said lip inserted into the last named 65 opening and with the free end of the lever

extending through the slot in the side of the housing, a post formed with a hole therethrough between its ends passing through the opening in the front of the housing, said tangs entering said hole in the post at opposite ends thereof, and with the inner end of the post passing into the opening adjacent the inner end of the latch lever, and a handle connected to the outer end of the post and depending therefrom, said handle being attached to the post so as to turn about the axis of the post, substantially as described. 70

2. A latch of the character described comprising a housing including a front and inwardly turned sides and ends, one of said sides being slotted and having an integral section turned inwardly under the front of the housing and spaced therefrom, a latch lever pivotally mounted between its 80 ends on said inturned section and extending through the slot in the side of the housing, a post passing through the front of the housing and pivotally mounted thereon between its ends to turn about a horizontal 85 axis, the inner end of the post having a pivotal connection with the inner end of the latch lever, and a handle connected to the outer end of the post and depending therefrom, said handle being attached to 90 the post to turn about the axis thereof, substantially as described. 95

3. A latch of the character described comprising a housing having a front and sides and ends, one of said sides being slotted and then turned inwardly under the front and spaced therefrom, a latch lever pivotally connected between its ends to said inwardly turned portion and extending through the slot in the side of the housing, a post passing through the front of the housing and pivotally mounted thereon between its ends, the inner end of the post having pivotal connection with the inner end of the latch lever, and a handle connected to the outer end of the post and depending therefrom, substantially as described. 100

4. A latch comprising a housing, a latch lever passing through a side of the housing and pivotally mounted between its ends within the housing, means including a depending handle associated with the latch lever for elevating the outer end of the lever, said handle being connected with the remaining parts of the elevating mechanism to turn about a horizontal axis to directly opposed positions with respect to the housing, substantially as described. 115

5. In combination, a door, a housing secured to the door, a latch lever pivotally mounted on and within the housing and extending at one end across the meeting edges of the door and the jamb therefor, a keeper secured to the door jamb, and 120

provided with a hook having an inclined outer edge and a vertical shoulder behind which the outer end of the lever is adapted to locate, a post pivotally mounted between its ends on the housing and extending through the front side of the housing, pivotal connections between the inner end of the post and the inner end of the latch lever, and a handle secured to the outer end 10 of the post and depending therefrom, substantially as described.

6. A latch comprising a housing, a latch lever pivotally mounted thereon and extending to one side of the housing, and 15 actuating means for the lever including a handle adapted to turn about a horizontal

axis to opposed positions with respect to the housing and latch lever, whereby the latch is adapted for attachment to doors swinging in either direction, substantially 20 as described.

7. A latch comprising a support, a latch lever pivotally mounted thereon, and actuating means including a movably mounted handle adapted to be turned to opposed 25 positions with respect to the support and latch lever, whereby the latch is adapted for attachment to doors swinging in either direction, substantially as described.

In testimony whereof I affix my signature. 30

HAROLD BLYE.
